UNITED STATES PATENT OFFICE.

STEPHEN GARRISON, OF BALTIMORE, MARYLAND.

DESIGN FOR A PICTURE-FRAME MOLDING.

Specification forming part of Design No. 6,742, dated July 1, 1873; application filed June 13, 1873.

To all whom it may concern:

Be it known that I, STEPHEN GARRISON, of the city of Baltimore, State of Maryland, have invented a new and original Design in Molding for Picture-Frames and other purposes, of which the following is a specification:

The object of my invention is to furnish a new, cheap, and tasty design in wood molding for the construction of picture-frames and other like purposes.

The nature of my design is fully represented in the accompanying photographic illustration, to which reference is made.

This illustration represents a section of a picture-frame in which the design of my molding is shown complete, the outer edge of which is ornamented with three plain parallel beads. These rise out of the body of the frame about one-sixteenth of an inch, and are grouped closely together, as shown at *c*, and are de-

nominated a trefoil. The inner edge or inner border of the molding is formed with a single bead, about three-sixteenths of an inch in size, back of which is a square or shoulder, while the central portion of the frame or molding is channeled, presenting a deep, broad, rounded groove; and the outside or edge of the frame or molding has what is known as an ogee configuration.

The essential element of my design is the trefoil or three parallel beads *c*, by which conformation or arrangement of the design I am enabled to furnish a molding which is very desirable to the trade in point of taste.

What I claim as my invention is—

The design for picture-frame molding, substantially as herein described and shown.
